[57] CLAIM

The ornamental design for an ultrasonic wave thickness meter, as shown and described.

DESCRIPTION

FIG. 1 is a front elevational view of an ultrasonic wave thickness meter showing our new design;

FIG. 2 is a rear elevational view thereof;

FIG. 3 is a right side elevational view thereof;

FIG. 4 is a left side elevational view thereof;

FIG. 5 is a top plan view thereof; and

FIG. 6 is a bottom plan view thereof.

FIG. 1

FIG. 2

FIG. 3**FIG. 4****FIG. 5****FIG. 6**
